UNITED STATES PATENT OFFICE.

HENRY A. OEHlke, OF LORAIN, OHIO.

DESIGN FOR A COLLAR-BUTTON.

47,543.

Specification for Design.

Patented July 6, 1915.

Application filed January 11, 1915. Serial No. 1,698. Term of patent 14 years.

To all whom it may concern:

Be it known that I, HENRY A. OEHlke, a citizen of the United States, residing at Lorain, in the county of Lorain and State of Ohio, have invented a new, original, and ornamental Design for Collar-Buttons, of which the following is a specification, reference being had to the accompanying drawing, forming part thereof.

a side elevation of a collar button, showing my new design.

I claim:

The ornamental design for a collar button, as shown.

HENRY A. OEHlke.

Witnesses:

GEO. N. DAMON,
C. E. VAN DEUSEN.
